SUPPLYING INK TO INK TRANSFER
MEMBERS

George E. Pelton, Aurora, Ill.

Application January 26, 1932, Serial No. 588,932

59 Claims. (Cl. 197—171)

This invention relates to typing machines, and particularly to means for supplying ink to the writing ribbons or transfer members of such machines while in use. The term "ink" is herein-after used to designate any transfer material for making marks or letters.

In my Patent No. 1,826,568 an ink absorbent supply ribbon is described from which ink is transferred to the writing ribbon. The present invention relates to improvements in what is shown in this patent.

The objects of this invention are to simplify the feeding of ink to a transfer member and to accurately control the rate at which ink is fed to the transfer member; also to make it possible to obtain as much writing from multi-color ribbons as from ribbons of one color; also to supply liquid ink from a source of supply to the transfer member in the form of a line or lines; also to place a line of ink from an ink reservoir upon an intermediate member from which it is in turn supplied to the ink transfer member; also to provide an intermediate member of this kind having a substantially impervious surface upon which the ink is placed for dispensing to the transfer member.

Other objects are to provide a method and apparatus of this kind, in accordance with which a small quantity of ink is picked up by the thin edge portion of a rotary member and transferred to that portion where the type contact to dispense ink, or the upper portion or lower portion, or an intermediate portion of the width of an ink transfer member, lengthwise, in the form of a thin or fine line or lines; also to provide a method and apparatus for transferring ink to a ribbon by using an intermediate or ink-conveying ribbon which receives a fine line or lines of ink of any desired shape, and which is wound upon the usual ribbon spools in contact with the writing ribbon; also to provide an apparatus of this kind in which a capillary member or wick of substantially cylindrical form extends into a supply of ink and rotates in contact with a thin edge portion of a disk or rotary member for applying a restricted supply of ink to the edge portion, and then transferring the ink to any desired portion of the ink transfer member; also to provide an ink dispensing mechanism which is so constructed that the wick which extends into the ink and the member contacting therewith are rotated by contact with a ribbon receiving ink from said rotary member; also to provide an apparatus of this kind by means of which the ink is fed from a reservoir through at least one minute orifice; also to pro-

vide an ink supply of this kind in which the discharge of ink from the orifice can be regulated and shut off when desired; also to secure from multi-color ribbons the same fine writing and same large quantity of writing as is secured by the present invention when single color ribbons are used; also to provide a new type of ink supply ribbon of materially less width than that of the writing ribbon and by means of which ink can be dispensed to any desired portion of a writing ribbon, either the upper portion where the type strike, the lower portion or any intermediate portion.

One of the main objects of this invention is to provide an ink supplying method and apparatus by means of which a fine thin writing ribbon or transfer member, such for example as disclosed in my co-pending application No. 567,111, can be used for a very long period of time to produce throughout its life uniformly fine writing resembling printing, and to use such a ribbon without change until the fabric itself is worn out.

In the accompanying drawings:

Fig. 12 is a fragmentary sectional view, on line 12—12, Fig. 9.

This invention may be applied to a typewriter or type mechanism of any kind employing a writing ribbon or other ink transfer member.

In the accompanying drawings, for the purpose of illustrating an embodiment of my invention, it is shown as applied to a typewriting machine having a frame 10 and a platen 11 which carries the paper or other material upon which the writing is done. 12 and 13 represent the usual ribbon spools upon which the writing ribbon 14 may be wound and unwound during the use of the typewriter. The ribbon in passing from one spool to the other passes through the usual ribbon guide or vibrator 15, and moves in the vibrator into and out of the writing position in which the ribbon is struck by the type. Any other means for using the ribbon to transfer ink therefrom to the writing surface may be employed.

In accordance with my improved method of supplying ink to a writing ribbon or other ink transfer member, I provide a rotatable member having a thin edge portion which, consequently, can receive only a very limited quantity of ink proportional to the thickness of the edge of the rotatable member. At one portion of the circular path of movement of the edge of the rotatable member, ink is applied to the edge, and at another portion of the path of movement of this edge, the ink is removed from this rotatable member and applied either directly to the writing ribbon or to an intermediate ribbon or carrier herein called an ink supply ribbon or member and which supplies the ink deposit thereon to the writing ribbon. The ink may be applied to the thin edge of the rotary member in any desired manner, for example, by having this edge contact or connect with, either directly or indirectly, a revolvable or a stationary wick or capillary member. To insure a uniform inking of this edge and to prevent the revolvable wick from being injured or cut by the thin edge of the rotary member, it is preferable to have the wick of cylindrical form and rotating at the same peripheral speed as the edge of the rotatable member. This insures a uniform deposit of ink on the edge of the rotary member, in that the portion of this member contacting with the wick applies very slight pressure thereto, and receives from said wick a small amount of ink which is deposited on the edge of the rotary member. The rotary member may however pick up ink directly or otherwise from a stationary wick or other ink feed means. The wick may be of tubular or any desired shape or form. When it is revolvable it may be in the shape of a cylinder and may be revolved by means of gears. The rotary members may receive their rotation from the movement of the writing or intermediate ribbon. The ink feed member may be of any desired shape or form. It may be of any material; it may be composed of more than one material and may be one unit or made up of more than one unit or it may be composed of several parts of different shapes and different materials. I do not in any way limit myself as to the ink feed used.

The apparatus for use in carrying out this method may be of any suitable or desired construction, that shown including a housing A containing the mechanism for applying the ink to a ribbon and also for guiding a ribbon into correct relation to the inking devices. This housing may be secured to any convenient part of the frame 10 of the typewriter machine in any suitable manner, lugs or brackets 16 being provided on the opposite

ends of the housing A in the construction shown, which lugs may be fastened by screws or other means to the frame or fixed part of the writing machine. In the particular construction shown, the housing A includes a rear wall 17 having suitable guide channels 18 and 19 secured to the inner surface of the wall, and spaced apart in the middle portion of the housing. In the construction shown in Figs. 1 to 5, 20 represents an intermediate or supply ribbon flexible member of any suitable or desired material, which may be wound on the spools 12 and 13 with the writing ribbon or ink transfer member 14 so that the ink carried by the supply ribbon will be supplied to the writing ribbon 14 when the supply ribbon contacts with the writing ribbon. This supply ribbon is preferably made of a non-metallic material that is impervious to or substantially non-absorbent of ink, or which has at least one smooth face which is impervious or non-absorbent, but if desired, for certain purposes, the supply ribbon may be made of any other material and even an absorbent or fabric material may be used. Preferably the ribbon is made as thin as possible. Examples of materials that may be used for making the supply ribbon include cellulose materials, cellophane, kodakoid, celluloid or paper, or combinations of these materials with fabric or fabric impregnated with substantially impervious cellulose compounds. This ribbon is guided in the channels 18 and 19, as clearly shown in Figs. 2, 4, and 5.

The housing A also has an ink reservoir 22 formed therein, which, in the construction shown, is of circular cross section and depends below the base 23 of the main portion of the housing A. The ink may be brought from the reservoir 22 by means of a wick or capillary member 25, a portion of which may be arranged to rotate about an axis. The wick may be substantially tubular in form and may be secured to the periphery of a cylinder 26 rotatable in the housing A and extending into the well 22. For example, the lower end of this cylinder may be journaled to rotate about the point of a screw 27 extending into the reservoir 22 through the bottom thereof and the upper end of the cylinder may be journaled in a bracket 28 secured to the side wall of the housing A and engaging a trunnion or bearing projection 29 of the cylinder 26.

30 represents a disk, wheel, or rotary member which is secured to a pivot or shaft 31 journaled at its upper and lower ends in bearing brackets or straps 32 and 33, secured on the base 23 of the housing A, but any other means for rotatably mounting the disk 30 or the wick supporting cylinder 26 may be employed, if desired. The disks are preferably provided with a series of holes 30a (see Figs. 5 and 6) which retard the spreading of the ink across the face of the disk, and thus prevent to a large extent the tendency of the ink to creep across the disk from the wick to the ribbon when the typewriter machine is not in use. Inks used in connection with typewriter ribbons and the like generally contain oil which has very great wetting or spreading power which property of the ink is of very little trouble in connection with this apparatus because of the very small areas of contact of the disk with the wick and ribbon, so that the holes 30a can be dispensed with without interfering with the successful operation of this method and apparatus (see disks shown in Fig. 7).

The disk or rotary member 30 may be made of any suitable non-absorptive material, such for example as metal, or other suitable relatively 75

rigid substance, and may be of any desired shape, so long as the edge portion thereof is sufficiently thin to carry the small amount of ink which is to be transferred to the desired portion of the ink transfer member. This rotary member 30 may, for example, be in the form of a thin disk, as shown in Figs. 3 and 4, of substantially uniform thickness, or a disk 30b of the shape shown in Fig. 6 may be employed in which the edge portion is serrated or recessed so that only parts of the edge portion of the disk engage the inking cylinder 25 and the ribbon, thus placing a broken or interrupted line in the form of a uniform series of short lines of ink upon the ribbon and thus reducing the amount of ink which will be placed on the ribbon or ink transfer member by the disk 30. For example, when the transfer ribbon 14 is used on a typewriting machine using pica or medium size, or small type or characters, for very neat work the edge of the disk 30 may have to be as thin as .002 of an inch in order not to supply an excess of ink to the transfer ribbon. For general classes of typewriting work on the usual, standard office typewriters, the edge portions of the disk, or the periphery of the disk may be as thin as .002 of an inch, or may be .004 of an inch or .006 of an inch in thickness, respectively, for pica or very small type; if the disk is of the shape shown in Fig. 6, the edge portions may be correspondingly thicker to put the same amount of ink in the lines of ink supplied to the writing ribbon. In connection with other typewriting machines, either typewriters having very large type or other machines using large or very large type, the edge of this disk may be very materially thicker, but preferably such thickness of disk is selected as will supply to the writing ribbon only enough ink to replace that which is removed during the writing, when the entire edge or periphery of the rotary member is coated with the ink. The thickness of the edge portion of said disk for neat writing should never be equal to the width of the space on the writing ribbon which is marked by the type. The periphery of the disk also may be of wavy or undulating form, or a plurality of disks may be employed, to deposit ink in a series of parallel lines on the writing ribbon and the term "line" as hereinafter used is intended to include one or more lines of either continuous, interrupted or broken, or undulating or irregular or any other form.

The disk or wheel 30, in the construction shown in Figs. 1 to 5, contacts with the supply ribbon 20 in the space between the adjacent ends of the two channel ribbon guide members 18 and 19, and in order to insure a uniform deposit of ink from the disk 30 on the ribbon 20, it may be desirable to press the ribbon against the disk 30. This can easily be done, as shown in Figs. 3 and 4, by means of a roller 34 pivoted on a bracket 35. These two parts may be contained in an extension 33 of the housing A on the rear wall thereof. The bracket itself forms one end or arm of a lever, pivoted at 36 in the bottom wall of the extension 33 of the housing A, and the other arm 37 of the lever has a spring 38, secured on the housing A, pressing against it so as to yieldingly swing the lever to hold the roller 34 against the back face of the ribbon 20 to press the front face of the ribbon against the edge of the disk 30. The spring may be of any suitable size or form; it may be used at any suitable place in connection with inking members, either those with gears or without gears; or with or without other driving connections. 40 represents a partition wall

extending lengthwise of the housing from end to end thereof, for preventing ink from contacting directly with the ribbon 20, or from escaping through the slots 41 and 42 in the ends of the housing through which the ribbon 20 enters the housing, in case the well 22 overflows. The partition wall 40 also makes it possible to fill the front portion of the housing with ink up as high as the upper edge of the partition wall 40, if desired, although for ordinary use, the amount of ink indicated in the well 22 in Fig. 3 is sufficient to insure an adequate supply of ink to the writing ribbon.

In order to prevent the wick or capillary member 25 from being cut or injured by the fine edge of the disk 30, because of relative movement of the contacting surfaces, the construction illustrated may be employed, in which the pivot 31 of the disk 30 carries a gear 45 meshing with a second gear 46 secured to the cylinder 26 carrying the wick. These gears are preferably of such size that the peripheral portions of the wick and of the disk 30 will be caused to move at the same peripheral speeds by the gears 45 and 46, so that there will be no relative movement between the edge of the disk 30 and the wick 25. Preferably, though not necessarily, the roller 34 is also provided with a gear 47 meshing with the gear 45 so that as the ribbon 20 is moved lengthwise through the housing by the rotation of either of the spools 12 and 13, the ribbon, by frictional contact with the roller 34 and the disk 30, will cause rotation of these two members, which is transmitted by the gears to the wick or capillary member 25. Other means for providing a driving connection between the disk and wick or the disk, wick and roller 34 may be employed, or if desired, these driving connections may be omitted.

49 represents a cover which fits over the top of the inking apparatus to exclude dust and prevent deterioration of the ink. It may be of any shape.

The construction described has the advantage that a line or lines of ink of uniform width usually narrower than the width of the type (or height) in the machine which is being used and containing a uniform amount of ink is always transferred to the upper portion, or where the type contact with the ribbon, or to the lower portion, or to any intermediate portion of a writing ribbon or to any portion of one face of the ink supply ribbon 20 by the disk 30. When the typewriter is not in use, as for example at night, the disk 30 will, of course, transfer no ink to the supply ribbon, and consequently, ink will only be supplied to the writing ribbon 14 exactly in proportion to the extent to which the ribbon is used, and only when the ribbon is used. Furthermore, the supply ribbon 20 is always wound upon that spool upon which the ribbon 14 is being wound, so that fresh ink is added to the portions of the writing ribbon leaving the writing position or vibrator 15. This allows ample time for complete absorption of the ink by the transfer member or ribbon 14 while it is wound upon the spool in contact with the ribbon 20, and said ink may be transferred to the ribbon 14 below that part where the type strike or to any part of the ribbon 14, either above or below or in the middle.

In Fig. 7 is illustrated an arrangement, whereby ink may be transferred directly to the writing ribbon 14. The apparatus shown may be of any suitable size and may be extremely small for use in portable typewriters and other small typ-

ing machines and it may be placed so as to transfer ink directly to the writing ribbon at any suitable point or place between the spool or spools and the ribbon guide or vibrator 15. In this connection a housing B of the inking apparatus has an arm 10 of the writing machine, and the housing B has an ink well or depressed portion 51 in which a wick member 52 similar to the wick 10 member 25 shown in Fig. 3 is arranged, the wick member contacting during its rotation with the disk 53, which in turn contacts with the ribbon 14. A roller 54 corresponding to the roller 34 shown in Figs. 2, 3 and 4 serves to press the ribbon into contact with the disk 53. In the use of a device of this kind, the ink is preferably applied directly to an edge portion of the writing ribbon 14. Gears connecting the wick 52, disk 53 and pressure roller 54, such as illustrated in Fig. 3 are not shown in Fig. 7 but are preferably also used in this modified form of my invention.

With either of the devices or inking means illustrated whether or not an ink supply ribbon is used, the inking device requires no attention, except at very long intervals (even for years) it may be necessary to replenish the ink in the reservoirs 22 or 51. No shutting off of the ink supply on discontinuing the use of the writing machine, nor turning on the supply on using the machine is necessary, since ink is only fed when either the supply ribbon or the writing ribbon moves through the ink applying mechanism and no transfer of ink takes place when the ribbon is not in use.

35 In Figs. 8 to 12 is shown a modified form of an ink feeding device in accordance with which a line of ink is fed from an ink supply through the medium of a minute orifice or orifices. This device is illustrated in these figures as applied to a typewriter similar to the one referred to in Figs. 1 to 7 and is illustrated as employed in connection with supply ribbon 20, which should be identical with the one shown in Figs. 1 to 7. In this case, an ink reservoir 65 is shown suitably secured to the front frame member of the typewriting machine, the reservoir being provided with a cover or top 67 which may be soldered or otherwise tightly secured to the reservoir to prevent the escape of ink, and the ink may be supplied to this reservoir through a short tube 68 having a screw cap 69 preferably provided with a small air aperture 70 therein.

The reservoir may be provided with any suitable or desired means or means hereinabove described including wicks and rotary members for feeding a fine line or lines of ink to the upper portion, or portion from which ink is dispensed in the act of writing, or portion marked by the type, or the lower portion, or any intermediate portion of a face of writing ribbon 14. The line of ink may be placed directly upon the upper, lower or any intermediate portion of a face of the writing ribbon, or the ink may be fed to a supply ribbon 20, which may also be wound upon the spools 12 and 13, and which is guided into position to receive ink.

Ink is fed from the reservoir 65 through a very small orifice, which, in the construction shown, is arranged in the outer tapering end of the tube or duct 75. The tube shown is arranged within the reservoir and extends through the rear wall 11 of the reservoir to a slight extent, so as to form a projecting nozzle extending beyond the rear wall of the reservoir. If desired, a valve may be employed for controlling and interrupting the

feed of ink through the orifice. In the particular construction shown, three of these orifices are used to obtain a wide range in the amount of ink that may be fed to the ribbon for the particular requirements of the work in hand. This arrangement is very desirable in many uses of typing machines. For example, the typist may do work on colored index cards requiring a large amount of ink in each impression so that the writing will be quite bold and stand out with strength and color clearly or the typist may require still more ink, in fact much more ink, so that she may fill in checks of colored paper getting plenty of ink into the paper itself to avoid danger of erasures, and she may do other kinds of work where more weight of ink is required in the impressions than for any ordinary job on white paper. Soon after, the work may all be on fine quality, very expensive white letter paper where a very slight feed of ink is sufficient for the best results. Structurally, the ink discharge members are all alike and the following description applies to them all.

In the construction shown, the end of each ink feed tube 75, opposite to the orifice 76, is provided with a threaded aperture 79 in which a correspondingly threaded portion 81 of a valve stem 80 engages, the stem having a knurled head 82 by means of which the same may be turned. The other end of the stem is provided with a part cooperating with the tube adjacent to the aperture 76 to regulate and interrupt the discharge of ink therethrough; this part, in the construction shown, being in the form of a tapered end 83 seating in a correspondingly tapered portion of the ink feed tube 75. Consequently, by turning the knob 82, the extent of opening of the aperture may be controlled and the flow of ink may be entirely interrupted.

The stems are preferably also provided with additional means for shutting off the supply of ink through the discharge apertures 76, and in the construction shown, each stem is provided with an enlarged cylindrical valve 85 fitting snugly within the ink supply tube 75 and this tube is provided with an opening 86 therein, which is normally closed by the valve 85. This valve 85, however, is provided with a longitudinal slot 88, through which ink may pass into the portion of the ink feed tube 75 leading to the discharge orifice. The slot 88 preferably terminates short of the opposite end of the cylinder 85, so that ink is kept out of that end of the tube and out of contact with the screw threads on the stem. It will be obvious that when the slot 88 is out of registration with the opening 86 in the ink supply tube, the supply of ink to the portion of the tube leading to the orifice is interrupted.

Means of any suitable kind may be provided for guiding a ribbon into correct relation to the discharge orifice 76. In the particular construction shown for this purpose, the ink reservoir 65 is provided with a guide member 90 which may be of any suitable form, that shown being pivoted at 91 near the front edge of the ink reservoir 65. A portion of this guide member 90 lies on the top of the ink reservoir and forms a second cover therefor, and the guide member also has a downwardly extending flange 92 on which suitable means for guiding the ribbon are arranged. In the particular construction shown, the face of the downwardly extending part 92 nearest to the discharge orifice is provided with a channel 94 which may be made of sheet metal bent to form flanges 95 and 96 extending toward

each other and leaving between them a slot large enough to expose the portion of the ribbon which is to receive the line of ink. The guide channel 94 is arranged to guide the ribbon into contact 5 with the discharge orifice or orifices. In the construction shown for this purpose, the channel contains a pad or cushion 98, see particularly Fig. 9, which pad is suitably secured to the inner face of the channel and which may be of any de-10 sired cushioning material tending to yieldingly press the ribbon against the discharge orifice, such as felt ribbon or cotton fabric, but any other suitable cushioning material may be em-15 ployed. The flanges 95 and 96 of the channel 15 may have suitable recesses 99 cut therein at the portions adjacent to the discharge orifices to permit the ribbon guide member to swing into operative position without striking the tapered ends of the ink supply tubes 76.

20 It has also been found of value to provide suitable means for stretching the ribbon across an orifice, and for this purpose the rear wall or face of the reservoir 85 is provided with a series of projections 100, one being arranged on each 25 side of this discharge orifice. The flanges 95 and 96 of the ribbon guide are also recessed as indicated at 101 to receive the projections 100. These 30 projections not only yieldingly press the ribbon against the pad 98 in the ribbon guide and thus produce a stretching of the ribbon across the orifice 76, but also serve to spread the line of ink fed to the intermediate member or ink-conveyor by the discharge orifice, so that this ink will be more quickly taken up by the writing ribbon. 35 Any other means for stretching the ribbon across the discharge orifice and for spreading the ink on the ribbon may be employed or these means may be entirely omitted.

It has also been found that in operating a type-40 writer equipped with medium sized type or pica type, or type smaller than pica such as elite or micro type and using an ink supply device of this kind, a very small quantity of ink is actually transferred by the type to the writing surface, 45 and consequently, only a very small amount of ink should be fed to the writing ribbon since otherwise the writing ribbon will be inked too heavily. For this reason, the orifices 26 are made very small. For an ordinary type of typewriting 50 machine having medium size type and for ordinary, plain, black impressions of fairly substantial weight of ink, an orifice of approximately .003 to .004 of an inch is quite sufficient to supply the necessary ink to the ribbon, but the size of 55 the orifice will, of course, depend somewhat upon the nature of the ink itself, as well as upon the nature of the writing to be done. For letter writing and for fine-cut impressions with pica or elite or micro type, I prefer an orifice .002 of 60 an inch in diameter, especially for white paper. In case a number of ink discharge orifices are em-65 ployed, as in the construction shown, the orifices may be of different sizes so that the operator can vary the extent of the ink supply in accordance with the work which is being done. For example, 70 in such cases the three orifices may be of .002, .004, and .006 of an inch in diameter, respectively. These sizes will cover all needs of most users of typing machines and result in a great 75 advantage from a writing standpoint. The .002 of an inch opening will feed a line of ink .002 of an inch wide therethrough; the .004 of an inch opening will feed a line of ink .004 of an inch wide or the .006 opening will feed a line of liquid ink .006 of an inch wide therethrough. The last size

will be sufficient for writing checks on colored paper where ink is required in such quantity as will permit it to get down into the substance of the check paper so as to saturate the paper fibres with ink, and is for very heavy writing generally. 5

By the use of ink feed mechanisms, such as de-10 scribed, it is possible to employ a very fine writing ribbon which may be very closely woven and as low as .002 of an inch in thickness, since the writing ribbon itself in this case is, of course, not depended upon to act as a reservoir for a supply of ink as in the case of typewriter ribbons now in use. A thin ribbon of this kind if made entirely of long fibre silk and friction calendered, as de-15 scribed in my application of October 5, 1931, is 15 extremely tough and will withstand the pounding of the type for a long period of time and also has the advantage of producing very fine cut, sharp, neat impressions. The writing ribbon is usually used with the friction calendered face portion to-20 wards the writing paper so as to secure the neatest writing on said paper, since the friction calendering gives a perfectly even, smooth, glossy surface to the fabric and on the side towards the writing paper, but when ink is placed upon the 25 face of the writing ribbon which is towards the writing surface, the ribbon may be used with the friction calendered face toward the type. For certain classes of work I much prefer, in addition to friction calendering the surface of the writing ribbon, to use the ink retarding types of ribbon 30 of my Patents No. 1,732,187, No. 1,830,559, No. 1,830,620 for writing ribbons in connection with the apparatus and equipment of the present invention. Said writing ribbons may be of any of 35 the weaves described in said patents, including "skip weaves" where one set of threads, either the warp threads or the filling threads, lies mostly on one surface of said ribbon. For the very finest writing ribbon for long service and the greatest 40 quantity of print-like writing, I prefer to use a ribbon, with either woven edges, or cut edges if properly fastened, of long fibre silk woven as de-45 scribed in my patent application of October 5, 1931, No. 567,111. I use a silk material that is 45 approximately .004 inch thick when the silk has been boiled off and the natural gum removed from the threads and the material singed in the usual manner and then I friction calender the material down to approximately .002 of an inch in thick-50 ness. This process is described in Patent No. 1,830,559. It is possible to use eighteen to twenty yards in length of this extremely thin writing ribbon and still have room for the ink supply ribbon herein described. Ink retarding 55 material such as the cellulose or pyroxylin de-55 scribed in my Patent No. 1,732,187, or the ink retarding means of my patents herein mentioned may be added to the calendered surface of this friction calendered ribbon. 60

In the case of multi-color ribbons the line or lines of ink can be readily transferred to that portion of the writing ribbon, which it is de-65 sired should receive the ink by raising or lowering the inking mechanism. In the case, for example, of a black and red writing ribbon used in combination with an ink reservoir and with an ink supply ribbon that is of materially less width than the writing ribbon, the ink reservoir or inking means is raised to the proper height to feed the 70 supply ribbon into the spool so as to wind on the spool well above the upper portion of the red ink portion of the writing ribbon or at least so that the line of ink on said supply ribbon is well above the upper portion of the red ink portion of the 75

said ribbon. At present bi-chrome ribbons and multi-color ribbons have a very limited life. This is specially true of a black and red ribbon which is used for correspondence and which is lightly inked. The black ink is soon used up and when only a slight amount of red ink has been used and when the fabric is in perfectly good condition, the ribbon is thrown away and time must be taken to put on a new ribbon because there was no 10
serve ink supply. It is rarely possible to use up all of the red ink when a writing ribbon 18 yds. to 20 yds. or longer is used in a typing machine equipped with my invention for maintaining a constant ink supply in the upper or black portion 15 while the fabric lasts, so it is really unnecessary to renew the red ink in the lower portion of the writing ribbon.

Any suitable means may be used for adjusting the elevation of the inking mechanism so that a 20
line of ink may be applied to any desired part of the writing ribbon. One form of construction that may be used for this purpose is illustrated in Figs. 8, 10, and 11 in which the inking mechanism is mounted on a base 110 having projecting ends 111 which are offset upwardly out of the plane of the base. These ends have apertures through 25
which extend screw studs 112 secured to the frame 10 of the typing machine. Nuts 113 and 114 are arranged on the threaded studs to engage the upper and lower faces of the ends 111 of the 30
base of the inking mechanism and by adjusting these nuts, the inking mechanism may be raised and lowered as shown, the mechanism being shown in its lowest position in the drawings. Any 35
other suitable adjusting mechanism may of course be applied to the inking mechanisms shown in Figs. 1 to 7.

By means of my invention one may place a 40
line, or lines, of ink upon the upper or black portion of a ribbon and get writing of as fine quality and as large quantity as when using a solid black writing ribbon. The ink is continuously fed in the right amount to replenish the amount used and just enough ink is kept at that part of the 45
writing ribbon throughout the length of said ribbon, where the type strike, to give extremely neat impressions of rich color. The typist may now depend upon a large ink reservoir built right into the typing machine to furnish the ink to the 50
multi-color ribbon and no longer does the upper portion have to carry its own black ink supply. There is another advantage in placing the ink upon the ink-conveying ribbon in the form of a line. One readily sees how extremely simple and easy it 55
is to convey from the ink reservoir to the writing ribbon a line of fresh ink that will always contain exactly the same amount of ink week in and week out for the entire life of the writing ribbon. The hard impervious surface of the ink supply ribbon 60
will not absorb any of the ink placed upon it so that the line of ink received by the absorbent surface of the writing ribbon is always the same throughout the life of the machine.

The present invention is a definite improvement 65
over the invention described in my Patent No. 1,826,568 because of the accuracy with which the ink supply can be controlled to supply ink only as it is used from the writing ribbon. This 70
is particularly true as to the multi-color ribbons. The small fine line of ink conveyed from the ink reservoir to the writing ribbon by the present invention and placed upon the writing ribbon well above the colored ink supply as a line of less width 75
than the height or width of the type of the typing

machine employing said writing ribbon and the said thin, fine line of ink so placed on the writing ribbon well away from the colored ink of said ribbon cannot possibly spread across into the colored ink and discolor same since the amount of ink fed to the writing ribbon is never sufficient to provide a surplus of ink that can cause harm by spreading into the other kind, or kinds, of ink in the writing ribbon. 5

By means of the constructions described, the 10
width and uniformity of line, or lines, of ink put on the writing ribbon can be controlled with a high degree of accuracy. In the construction shown in Figs. 1 to 7, this can be done by controlling the thickness of the outer edge of the 15
disk 30. It will also be understood that a number of disks of any suitable kinds or sizes of edges or periphery portions may be employed for placing a plurality of lines on any desired portions of the 20
ink transfer member, if necessary. The term "lines of ink" is herein used to include broken lines as well as continuous lines or lines of any other kind. Broken lines may be formed by the 25
disk shown in Fig. 6. They may be extremely thin short lines, or dashes that are so small and so extremely thin as to look to the naked eye like a series of very fine dots extremely close to one another. I prefer to use a very quick flowing, 30
extremely thin ink when making a series of extremely close dots or dashes so that the ink will, almost immediately after it touches the surface of the writing ribbon, flow across and entirely close up the spaces between the dots or dashes thereby making a connected line or lines. 35

By means of the construction shown in Figs. 8 to 11, it will be obvious that the ink supply may be controlled by selecting an orifice of the desired size or by placing a number of lines of ink on the ribbon by means of a number of orifices at one time. In this construction, the ink supply may be shut off, when the typewriter is not in use, by closing the ink supply valves. 40

As a result of the ink feed mechanisms described, it is possible to employ and operate a machine for a much longer period if a suitable writing ribbon is employed such, for example, as ribbons of the kind described in Patents No. 1,732,187, No. 1,830,559, No. 1,830,620 and application No. 567,111 of October 5, 1931, without changing the writing ribbon since obviously the only limit as to quantity of writing of uniform appearance (and that matches substantially and for all practical purposes from its first use until the fabric is worn) is set by the length of time the ribbon fabric can withstand the pounding or pressure of the type against the same, and not upon the amount of ink stored in the ribbon. The beauty of the writing is dependent upon the writing ribbon's quality and upon uniform feed of ink to the same in the right amount. In machines in which the type is pressed against the ribbon rather than hammered or struck against the same, the wear on the ribbon is very much less than in an ordinary typewriter, so that the life of a ribbon under such pressure is for some years, and throughout its life the writing done by the ribbon will be of uniform weight of ink, very sharp and clear and of excellent color. No matter how long the particular piece of typewriting work may be, the writing on the last page will be of as rich color and as easily legible as that on the first page. It is well known that finely woven, thin, high thread count, silk ribbons produce much finer writing than usual cotton rib- 50

bons, but as ordinarily used up to the present time, the ribbon must also serve as the sole reservoir for the ink supply. In accordance with this invention, it is unnecessary to carry more than a temporary ink supply in the writing ribbon. Consequently, the finest kind of long fibre silk typewriter ribbon, made as described in the before mentioned patents and application for patents, can be used as a writing ribbon, so that by the use of my present invention, not only is the writing of uniform color throughout the life of the ribbon, but also the impressions are much finer than those obtained by typewriter ribbons as heretofore commonly used. It is very economical to use a long fibre silk writing ribbon of the high excellence of yarn and weave described in application No. 567,111 (woven .004 of an inch in thickness and brought down to .002 of an inch by friction calendering) in conjunction with this present invention. For example, one face of a ribbon of this kind can be friction calendered to cause this face to retard to a certain extent the passage of ink through this surface, or a face of a ribbon may be coated with an ink retarding cellulose compound solution as described in my Patent No. 1,732,187. The ink from the ink reservoir or ink supply ribbon may then be applied to the uncalendered or uncoated face of the ribbon.

30 The inking mechanisms described herein can be built extremely small and compact so they can be used on the smallest portable machines now made. When an inking means such as described is used, the ribbon spools are made larger than standard. Also when the ink is fed directly to the writing ribbon as shown in Fig. 7, I prefer to use a larger spool or spools. The longer the writing ribbon, the more even, neat, uniform writing that substantially matches, can be done without having to change ribbons, either by bringing the lower portion of the ribbon above or by putting on a new ribbon.

Writing ribbons have heretofore been reinked after the first ink supply has been exhausted by taking the ribbon off the machine and then applying a large amount of ink which results in a ribbon that writes very heavy and ugly. A material commonly used in reinking is oil which contains no pigment and no dye. After the ribbon has been reinked it is usually allowed to stand for a few days before being placed back on the machine. This again results in writing that is too heavy at the start. The color and weight of the ink in the impression changes steadily until the writing again becomes dim and gray. My present invention gives uniform color and substantially the same quantity of ink in the impression when the fabric is new and when the fabric is nearly worn out, and during all the long period in between.

There is another advantage in using the present invention. Because the only thing that limits the amount of writing that may be done by a ribbon with my inking mechanism is the life of the fabric, and because there is always a fine ink supply in reserve, it being a simple matter to refill the ink reservoir, it is practical for the typist when the upper portion of the ribbon becomes worn, to remove the writing ribbon and rewind it with the bottom edge placed above in the machine and on the spools. If this is done, the writing ribbon is again good for another very long period of use equal to the first period of use. This, of course, is limited to solid color ribbons. It is not customary at present to turn

over the solid color ribbons so as to bring the lower edge above and so as to furnish new unused fabric in the portion or line of the ribbon where the type strike. Present solid color ribbons are made so that the ink in the lower half of the ribbon travels to the upper half so that when the typist has exhausted the ink in the upper half, the lower half of the ribbon will be found quite dry and with so little writing capacity that it is considered impractical to use the lower portion of the solid color ribbon. The present invention, however, makes it advisable for the purchaser of a machine to purchase that type of machine which enables one to not only use the space of the ribbon above mentioned but also permits other portions of the fabric to be used, a mechanism for making different parts of the ribbon usable being, for example, shown in my Patent No. 1,324,265 of December 9, 1919, so that the typist may readily use the entire width of the fabric of the writing ribbon before throwing the writing ribbon away. At present most ribbons and especially the expensive commercial silk ribbons which carry so little ink in order to do sharp writing, and especially all lightly inked ribbons, are thrown away when the fabric is in fine condition and simply because the ink is gone.

It will, of course, be understood that the devices described may be used on any typing or printing mechanisms employing type and a transfer member, whether said member is in the form of a ribbon, sheet, or any other form.

While in this description the ink has been described as a liquid, yet it is to be understood that any other transfer material which may be placed upon the edge of a disk or rotary member as needed, and in turn placed upon the surface of the ink transfer member, may be employed. It is to be understood that the construction shown is for purposes of illustration and that variations may be made in sizes and styles of parts and in details without departing from the scope and the spirit of the present invention. I do not limit myself as to the kind of materials used in the ribbons or in the rotary members or wicks, or any other parts and I do not limit myself as to the kind of writing ribbon used or as to its width or length or as to the kind of material used in the ink supply ribbon or as to its length or width or thickness. And I do not limit myself as to the reservoir, or reservoirs used.

With reference to commercial or standard typewriter ribbons of good quality of cotton fabric, it is understood that the usual heavily inked ribbon in an average office will be used approximately 5½ days a week for perhaps five weeks where the typist takes dictation in shorthand; that the medium inked ribbon under like conditions will be used approximately three and one-half to four weeks and the standard lightly inked ribbon or clean inked secretarial ribbon will be used for from two to three weeks. If the lightly inked ribbon is used almost continuously for as much as five hours a day by the typist who is rapid and takes no shorthand dictation, it is to be understood that the standard lightly inked ribbon will last for approximately four or five days before the ink supply is so exhausted that it is of no value whatever. In other words the standard lightly inked ribbon would contain very little ink when first put in use so that its writing might be as neat as possible from the outset and when used for a total of approximately twenty-four hours by a rapid typist, its ink supply would be exhausted to a degree that

it was of no value and would have to be replaced by a new ribbon if used in the usual way on a typewriter not equipped with an inking means. Commercial silk ribbons are understood to be the usual high priced ribbons which have a very limited use and are luxury products which usually do not carry much ink and have slight ink absorbing capacity. The fact is well known that the hard fibers of usual commercial silk typewriter ribbons cannot absorb ink in comparison with cotton ribbons of good grade, closely woven, retailing for slightly less than the price of the said commercial silk ribbons. Commercial silk typewriter ribbons have but slight ink-absorbing capacity and ink storage capacity per unit area but may be of a thinness to produce written characters of sharp, neat outlines when medium inked or lightly inked. If heavily inked, such silk ribbons usually carry a large amount of surface ink which is very oily and gives poor outlines in the writing. Due to the silk fabric being much freer from lint and fuzz than cotton ribbons, it is possible for medium inked silk ribbons to produce sharp, neat impressions of rich color but this color wears down materially in the hands of a rapid typist so that within two weeks such a medium inked ribbon writes faintly. Two weeks is understood to be a very short life for a standard typewriter ribbon of medium inked type, standard length of twelve yards. The vast majority of typists are never given such ribbons because they so soon contain very little ink and are considered extravagant.

I claim as my invention:

1. In a typing machine, the combination of a writing ribbon, an ink reservoir, a non-absorbent ink supply ribbon having a surface adapted to contact with the writing ribbon, means for placing ink from said reservoir upon said surface of said ink supply ribbon.

2. In a typing machine, the combination of a writing ribbon having an absorbent body portion and a frictioned calendered ink retarding face portion, an ink reservoir, an ink supply ribbon, said ribbons contacting with each other, means for moving the writing ribbon between the surface to be typed and the type, and means for transferring ink from said ink reservoir to said ink supply ribbon in proportion to the amount of travel of said writing ribbon.

3. In a typing machine, the combination of a two color writing ribbon, having an absorbent body portion and a friction calendered face portion, an ink reservoir, an ink conveying supply ribbon of less width than said writing ribbon, the two ribbons contacting with each other at one side of the division line between the two colors of ink of the writing ribbon, to replenish the ink supply of one color portion of said ribbon.

4. In a typing machine, the combination of a writing ribbon, the lower half of which contains red ink and the upper half of which contains an ink other than red, an ink reservoir containing ink corresponding in color to said other ink, a substantially non-absorbent ink supply ribbon which is less than half the width of the writing ribbon, the two ribbons contacting with each other above the division line between the inks so that the red ink portion of the writing ribbon remains out of contact with the ink supply ribbon.

5. In a typing machine, the combination of a writing ribbon, the lower half of which contains red record ink and the upper half of same contains ink other than red, an ink reservoir containing ink corresponding in color to said other

than red ink, a substantially non-absorbent ink supply ribbon which is less than half the width of the writing ribbon, the two ribbons contacting with each other above the red ink portion of the writing ribbon so that the red ink portion of said writing ribbon remains out of contact with the ink supply ribbon, means for placing ink from said ink reservoir upon said ink supply ribbon, and means for transferring said ink from said ink supply ribbon to said writing ribbon lengthwise thereof and above said red ink portion of said writing ribbon.

6. In a typing machine, the combination of a writing ribbon, the lower half of which contains a different ink from the upper half, an ink reservoir containing ink free from pigment but containing dye of the desired color, a substantially non-absorbent ink supply ribbon which is less than half the width of the writing ribbon, the two ribbons contacting with each other throughout substantially their length but the ink supply ribbon contacting with no portion of one half of said writing ribbon and conveying no ink from said ink reservoir to said half of the writing ribbon with which it does not contact.

7. In a typing machine, the combination of a writing ribbon, the lower half of which contains a different ink from the upper half, an ink reservoir containing ink of a color and composition suitable for blending with one of the inks in said writing ribbon, a substantially non-absorbent ink supply ribbon which is less than half the width of the writing ribbon, a pair of spools upon which the two ribbons are inter-wound, and means for unwinding the ribbons from one spool and winding them upon the other, the writing ribbon in passing from one spool to the other, passing between the type and the surface to be typed while the supply ribbon passes in contact with the ink supply mechanism and ink reservoir and means for placing ink upon said supply ribbon of a color and composition suitable for blending with one of the inks in said writing ribbon and means for guiding said supply ribbon for transferring said ink from the supply ribbon to the proper portion of the writing ribbon.

8. In a typing machine, the combination of a writing ribbon having an absorbent body portion and a friction calendered ink-retarding face portion, means for moving the writing ribbon between the type and the surface to be typed, an ink reservoir, an ink supply ribbon, means for transferring ink in uniform amounts from said ink reservoir to said ink supply ribbon, and means for guiding said ribbons into contact with each other for transferring ink from said ink supply ribbon to that face of said writing ribbon opposite to said ink retarding face portion.

9. In a typing machine, the combination of a writing ribbon having an absorbent body portion and a friction calendered, ink-retarding face portion, and means for moving the writing ribbon between the type and the surface to be typed, an ink reservoir, an ink supply ribbon, means for transferring ink in uniform amounts from said ink reservoir to said ink supply ribbon, and means for guiding said ribbons into contact with each other for transferring said ink from said ink supply ribbon to said writing ribbon in the form of a fine line or lines, to the upper portion where the type contact or dispense ink from the ribbon or strike the ribbon, or the lower portion, or any intermediate portion of one face of the writing ribbon and throughout substantially the writing length of the said writing ribbon as indicated by

the length of the space marked by the type along said writing ribbon and along one face thereof.

10. In a typing machine, the combination of a writing ribbon having an absorbent body portion and a friction calendered, ink-retarding face portion, means for moving the writing ribbon between the type and the surface to be typed, an ink reservoir, an ink supply ribbon, the ribbons contacting with each other throughout substantially their entire length, and means for transferring ink in uniform amounts from said ink reservoir to said ink supply ribbon, said ink being transferred from said ink supply ribbon to said writing ribbon in the form of a line.

15 11. In a typing machine, the combination of a writing ribbon having an ink-retarding, friction calendered face portion and an absorbent body portion, an ink reservoir containing a large supply of ink, means for moving the writing ribbon between the type and the surface to be typed, a substantially non-ink absorbent ink supply ribbon having an even, smooth surface for receiving said ink from said ink reservoir, and means for controlling the feed of said ink upon the ink supply ribbon in the form of a line of ink of any desired size, shape or form, and means for bringing the ink carrying face of said ribbon into contact with the non-ink-retarding face of the said writing ribbon to transfer ink from said supply

25 30 ribbon to said writing ribbon.

12. In a typing machine, the combination of a friction-calendered writing ribbon, means for moving the writing ribbon between the type and the surface to be typed, a non-fabric, non-absorbent ink supply ribbon with at least one smooth surface, the ink supply ribbon contacting with the upper portion, or with the lower portion, or with any intermediate portion of the writing ribbon, lengthwise and substantially throughout the entire length of said writing ribbon, said ink supply ribbon being movable in contact with the writing ribbon, said ink supply ribbon not exceeding three-sixteenths ($\frac{3}{16}$) of an inch in width, an ink reservoir for supplying ink to said ink supply ribbon for transfer to the writing ribbon.

13. A typing machine, including a capillary member composed largely of absorbent fibres and being of substantially cylindrical form rotatable about an axis, a supply of liquid ink into which a portion of said capillary member extends during the rotation thereof, another portion of said capillary member being permanently arranged out of said ink supply, a rotary member having an edge portion in rolling contact with said other portion of said capillary member, and a ribbon movable in contact with said rotary member for receiving ink from said edge.

14. A typing machine, including a capillary member composed largely of absorbent fibres and being of substantially cylindrical form rotatable about an axis, a supply of liquid ink into which a portion of said capillary member extends during the rotation thereof, another portion of said capillary member being permanently arranged out of said ink supply, a rotary member having its entire edge portion in rolling contact with said other portion of said capillary member, a ribbon movable in contact with said rotary member for receiving ink from said edge, and means for yieldingly pressing said ribbon into engagement with said edge portion.

15. The combination of a capillary member composed largely of absorbent fibres and being of substantially cylindrical form having an ab-

sorbed supply of liquid ink, a rotary member having an edge portion thereof in rolling contact with said capillary member to receive ink therefrom on said edge portion, a ribbon moving in contact with the edge portion of said rotary member to receive ink from the entire periphery or edge portion and to impart rotary motion to said rotary member, and a driving connection between said rotary member and said capillary member.

16. The combination of an ink transfer member, a non-metallic non-absorptive ink supply member, a reservoir for a supply of liquid ink, having at least one discharge orifice with which said supply member contacts and through which ink from said reservoir may be discharged and means for bringing said supply member into at least some contact with said transfer member to transfer the ink on said supply member to the upper portion, or the portion where the type contact or from which they dispense ink to a surface, or the lower portion of one face, or any intermediate portion of one face of said transfer member throughout the entire length of the writing space portion of said ink transfer member.

17. The combination with an ink transfer member, of a reservoir of liquid ink, means for transferring ink from said reservoir to said transfer member in the form of at least one line, and means for controlling and regulating the discharge of ink from said reservoir through at least one orifice to the upper portion, or the portion from which ink is dispensed to a surface, or the lower portion of one face, or any intermediate portion of one face of said transfer member.

18. The combination with an ink transfer member, of a reservoir for liquid ink, and a plurality of minute discharge orifices of different sizes for gravitationally discharging ink from said reservoir for absorption by said transfer member, and means for controlling the discharge of ink through said orifices to feed exactly the correct amount of ink to the transfer member throughout the life of its fabric, for requirements that call for several different feeds of ink, some feeds larger than others, and means for always feeding ink in differing quantities that shall always be uniform quantities.

19. The combination with an ink transfer member, of a reservoir for liquid ink, and a plurality of minute discharge orifices for gravitationally discharging ink from said reservoir for absorption by said transfer member, and means for controlling the amount of ink supplied to said transfer member by interrupting the discharge of ink through any of said discharge orifices.

20. The combination with an ink transfer member, of a reservoir for a supply of liquid ink, having at least one discharge orifice, a non-metallic intermediate member for receiving ink from said orifice, said intermediate member contacting with said transfer member to transfer ink from said intermediate member to the upper portion, or the portion from which ink is dispensed to a surface, or the lower portion of a face, or any intermediate portion of one face of said transfer member, and means for controlling the discharge of ink through said orifice to said intermediate member.

21. In a writing machine employing an ink transfer member, the combination of a reservoir for liquid ink mounted on said machine, a capillary discharge orifice for transferring ink from said reservoir to the upper portion, or the portion from which ink is dispensed to a surface, or the lower portion of a face, or any intermediate portion of one face of said transfer member, and

- valve means which may be opened or closed by the typist as desired, or may be partially opened as desired for controlling the discharge of ink through said orifice.
- 5 22. In a typing machine, the combination with an ink transfer member, of an inking mechanism mounted on said machine for supplying ink to said transfer member, and means for supporting said inking mechanism in different positions relatively to said machine for supplying ink to the upper portion, or the portion from which ink is dispensed to a surface, or the lower portion of a face, or any intermediate portion of one face of said transfer member.
- 10 23. In a typing machine, the combination with an ink transfer member, of an inking mechanism and a reservoir of ink containing an inked wick, and said inking mechanism including a rotary disk having a thin periphery portion which is inked by ink from the end portion of said wick and said inking mechanism being distinguished by its ability to place an extremely thin line or lines of ink upon a surface of a transfer member lengthwise thereof and for the full space of said 15 member which is touched or struck by the type or with which the type contact in dispensing ink to a surface, and said lines or line of ink being of the same width of ink and same weight of ink out to the ends of the writing space of 20 said transfer member as at any other part of said member's writing space or space where the type contact or where the type mark the transfer member and said typing machine having adjustable means for mounting said inking mechanism on said machine, said means being adjustable to raise and lower said inking mechanism with reference to said ink transfer member for supplying ink to different portions of said ink transfer member.
- 25 24. In a typing machine, the combination of a reservoir of ink, a woven ink transfer ribbon comprising a set of warp threads and a set of weft threads so woven that the threads of one set are exposed to a greater extent on the face adjacent the surface to be typed, at least one set of said threads being mainly of long fibres of animal silk, and means for feeding ink from said reservoir to said transfer ribbon in said machine while the same is in use intermittently, to maintain an approximately uniform amount of ink in the writing ribbon at the typing position; said typing machine being equipped with at least one 30 ribbon.
- 35 25. In a typing mechanism, the combination of an ink transfer ribbon woven of long fibres of animal silk of high thread count and having a friction calendered surface with an ink retarding material thereon, and means for placing ink on said ribbon during its intermittent use in said 35 typing mechanism in approximately uniform amounts thereby maintaining substantially uniform amounts of ink in that lengthwise portion of said ink transfer ribbon which is contacted by the type at the writing position.
- 40 26. The method of maintaining an ink transfer member in an inked condition so that it carries substantially the same amount of ink as when first put into use at all times during the intermittent operation of a typing machine, 45 which includes the step of feeding ink by gravity from a minute orifice in a continuous line to a face of a transfer member during intermittent operation of said machine and controlling the rate of discharge of said ink through said orifice
- 50 said machine being equipped with at least one ribbon.
- 55 27. In a typing machine, the combination of a reservoir of ink, an ink transfer member having an absorbent body portion and an ink-retarding face portion and means for supplying ink from said reservoir to the absorbent body portion of said transfer member in the form of a line of less width than the width of that portion of said transfer member which is marked by the type during operation of said machine.
- 60 28. A printing machine of the kind wherein a printing ribbon is reeled alternately on two different spools during operation of said machine, characterized in that said machine is provided with re-inking means for the printing ribbon, comprising a non-printing, ink-carrier ribbon which is relatively narrow and thin as compared with the printing ribbon and which interwinds face to face with the printing ribbon on 65 said spools adjacent one longitudinal edge of the printing ribbon for carrying ink to said printing ribbon while reeled upon each spool, said non-printing ribbon being substantially impervious and non-ink-absorbent.
- 70 29. In a printing machine, the combination of a printing ribbon impregnated with ink, a non-absorptive ribbon adapted to receive and transfer ink to said printing ribbon, means for causing an inked side of the non-absorptive ribbon to contact progressively with the printing ribbon, printing means coactive with the printing ribbon to form inked impressions, guiding means for the non-absorptive ribbon withholding the same 75 from the field of printing action of the printing means, a pulley supported on an axis and engaged and driven by said non-absorptive ribbon, an ink applying disk supported to rotate about an axis parallel to the pulley axis to contact one face of said non-absorptive ribbon at a point where the opposite face is in contact with said pulley, an ink reservoir below the level of the disk, said pulley and disk being rotatively driven by said non-absorptive ribbon, and a wick means extending into said reservoir for conveying ink from the reservoir and applying a film of ink to the periphery of the disk.
- 80 30. In a typing machine, the combination of a writing ribbon, the lower half of which contains a different ink from the upper half, an ink reservoir containing ink of a color and composition suitable for blending with one of the inks in said writing ribbon, a substantially non-absorbent ink supply ribbon, a pair of spools upon which the two ribbons are interwound, and means for unwinding the ribbons from one spool and winding them upon the other, the writing ribbon in passing from one spool to the other, passing between the type and the surface to be typed while the supply ribbon passes in contact with the ink supply mechanism and ink reservoir and means for placing ink upon said supply ribbon of a color and composition suitable for blending with one of the inks in said writing ribbon and means for transferring said ink from the supply ribbon to the proper portion of a face of said writing ribbon.
- 85 31. A typing machine ribbon spool having interwound thereon an absorbent writing ribbon and a substantially non-absorbent ink carrier ribbon.
- 90 32. In a typing machine, the combination of a writing ribbon, an ink reservoir, containing a portion of an inked wick and containing ink, an

ink supply ribbon having at least one even, smooth surface for receiving ink without absorbing the same, means for placing said ink from said wick upon said ink supply ribbon in uniformly even quantities, and means which move said ribbons and guiding means for guiding said ribbons into proper position on the winding spools, and means for guiding said supply ribbon to a position for transferring ink from said supply ribbon accurately to the upper portion, lower portion, or any intermediate portion of a face of said writing ribbon throughout substantially its length.

33. In a printing machine, the combination of a printing ribbon impregnated with ink, a non-absorptive ribbon adapted to receive and transfer ink to said printing ribbon, means for causing an inked side of the non-absorptive ribbon to contact progressively with the printing ribbon, printing means coactive with the printing ribbon to form inked impressions, guiding means for the non-absorptive ribbon withholding the same from the field of printing action of the printing means, a pulley engaged and driven by said non-printing ribbon, an ink supply disk supported to rotate about an axis parallel to the pulley axis, yielding means for effecting relative movement of said pulley and disk to urge one toward the other to cause said disk to contact one face of said non-absorptive ribbon at a point where the opposite face is in contact with said pulley, an ink reservoir below the level of said disk, a roller supported to rotate about an axis parallel to that of said pulley and disk and contacted at its periphery by said disk, said pulley, disk, and roller being rotatively driven by said non-absorptive ribbon, and a wick means extending into said reservoir from the periphery of said roller for conveying ink from the reservoir and applying a film of ink to the periphery of the roller.

34. In a typing machine, the combination of a writing ribbon, an ink reservoir, a non-absorbent ink supply ribbon having a surface adapted to contact with the writing ribbon, and means having a rolling contact with said supply ribbon and receiving ink from said reservoir and depositing it on said supply ribbon.

35. The combination with an inked writing ribbon of a typing machine and a reservoir of fluid ink, of a rotary wick member, one end of which rotates in said ink and the other end of which rotates outside the ink in said reservoir, means contacting with said other portion of said wick for receiving ink therefrom and for transferring the same to said writing ribbon in correct amounts during intermittent operation of said machine to replace ink used in writing.

36. In a typing machine employing an ink transfer ribbon member, the combination of a disk rotatable with its edge in contact with said ink transfer member, a pulley having a rolling contact with the opposite face of said transfer member, rotary means connected with an ink supply, including a rotary member which contacts with the periphery of said disk and applies ink thereto and means for transferring said ink from said ink supply to a ribbon member in said machine in correct amounts during intermittent operation of said machine to replace ink used in writing; said disk lying in an approximately horizontal plane and being geared for positive movement during operation of said typing machine.

37. In a typing machine, the combination of a writing ribbon, means for traversing said ribbon

longitudinally past a typing position, the portion of said ribbon located at the printing position being in an approximately vertical plane, an ink reservoir, a rotary inking disk and a roller arranged at opposite sides of a ribbon in said machine, said disk lying in an approximately horizontal plane; means for applying a predetermined, accurately gauged, quantity of ink from said reservoir to the periphery of said disk during intermittent operation of said machine, for transfer by suitable means to said writing ribbon to restore to it a quantity of ink approximately equal to that expelled during each traverse of said writing ribbon past said typing position thereby maintaining a substantially uniform amount of ink in said writing ribbon regardless of intermittent operation of said machine.

38. In a typing machine, the combination of a writing ribbon, means for traversing said ribbon longitudinally past a typing position, an ink reservoir, a rotary inking disk and a roller lying on opposite sides of a ribbon in said machine, said disk lying in an approximately horizontal plane; means for maintaining an approximately uniform supply of ink in said writing ribbon at the typing position, including means for applying a line of ink in the form of a thin, narrow film, to the edge of said disk during intermittent operation of said machine for transfer from said edge to said writing ribbon to replace approximately the amount of ink expended in writing during each trip of the writing ribbon; said disk being positioned out of direct contact with the ink supply in said reservoir.

39. A typing machine according to claim 38 in which gears connect said disk with a roller in said machine.

40. In a typewriter equipped with an inked ribbon of little ink storage capacity per unit area and of a thinness to produce written characters of sharp outline, the combination of an ink reservoir and means for maintaining an approximately uniform supply of ink in said inked ribbon at the typing position, and including means for placing ink from said reservoir upon a face of a ribbon in said typewriter, said means including a thin edged inking wheel having a rolling contact with a face of a ribbon in said typewriter for depositing ink thereon in predetermined, accurately gauged quantity during intermittent operation of said typewriter; said inking wheel lying in an approximately horizontal plane and lying above and outside the ink in said reservoir.

41. In a typewriter equipped with a writing ribbon, lightly impregnated with ink for sharp, neat writing, the combination of means for reinking said writing ribbon during intermittent operation of said typewriter, including rotary means, and including a thin edged inking wheel lying on one side of a ribbon in said typewriter, and a pulley lying opposite said wheel and contacting the other side of a ribbon in said typewriter; gears connecting said wheel and pulley, and means for applying ink from a reservoir in said typewriter upon the edge of said wheel in predetermined, accurately gauged quantity to replace the ink used from the writing ribbon; said wheel lying in an approximately horizontal position, above and outside the ink supply in said reservoir.

42. In a typing machine, the combination of a highly wear resistant writing ribbon including fibres of silk, an ink reservoir, a substantially non-ink absorptive ink supply ribbon having a surface adapted to contact with said writing ribbon

bon and means having a rolling contact with said supply ribbon and receiving ink from said reservoir and depositing it on said supply ribbon in predetermined, accurately gauged amounts.

43. In a typing machine, the combination of a writing ribbon, including fibres of silk, carrying the optimum quantity of ink for neat imprints, a substantially non-ink-absorptive supply ribbon having at least one smooth, even surface, the two ribbons interwinding on the spools, an ink reservoir, and means for placing a predetermined, accurately gauged amount of ink from said reservoir upon a face of said supply ribbon and means for moving said ribbons during operation of said machine so as to transfer said ink from said supply ribbon to said writing ribbon in correct amounts to replace ink used from said writing ribbon.

44. Mechanism for supplying ink to an ink transfer member in a typing machine, to maintain an approximately uniform supply of ink in a writing ribbon at the typing position during intermittent operation of said mechanism, including rotary means and including a thin-edged, ink-carrying disk, an ink reservoir, means for placing ink from said reservoir in predetermined, accurately gauged amounts upon the edge of said disk, a pulley; said disk and pulley lying on opposite sides of said transfer member; means for yieldingly pressing said disk and pulley towards each other and against opposite faces of said transfer member; suitable gears connecting said disk with at least one other rotary member in said machine; said disk lying in an approximately horizontal plane outside the ink in said reservoir; said mechanism being equipped with at least one ribbon.

45. Device for supplying ink to a ribbon member in a typewriter as said ribbon travels back and forth during operation of said typewriter, to maintain an approximately uniform supply of ink in a ribbon member of said typewriter at the typing position, comprising a pulley rotated by contact with a face of a ribbon member; an ink applier which is in driving connection with said pulley and is actuated by rotation of the latter to apply ink to the other face of a ribbon member; an ink reservoir whose ink supply lies below said pulley and below said ink applier; said ink being placed on said face of a ribbon member by said ink applier in predetermined amounts, accurately gauged, during intermittent operation of said typewriter.

46. Device according to claim 45 characterized in that the ink applier is a disk lying in an approximately horizontal position geared to said pulley and supported to rotate on an axis parallel to the pulley axis and to peripherally contact a face of a ribbon fed between the pulley and disk with the opposite face of the ribbon engaging the periphery of the pulley.

47. Device according to claim 46 characterized in that a roller peripherally contacts the ink applier disk and is geared to said disk for rotative driving of the roller and ink is fed to the roller from the ink reservoir.

48. In a printing machine, the combination of an inked printing ribbon, a non-printing ribbon adapted to receive and transfer ink to said printing ribbon, means for causing an inked side of the non-printing ribbon to contact progressively with the printing ribbon, printing means coactive with the printing ribbon to form inked im-pressions, guiding means for the non-printing

ribbon withholding the same from the field of printing action of the printing means, a pulley supported on an axis and engaged and driven by said non-printing ribbon, an ink-supplying disk supported to rotate about an axis parallel to the pulley axis, said non-printing ribbon passing between said pulley and said disk and said ribbon and disk being yieldingly urged into contact at a point where the opposite face of said non-printing ribbon is in contact with said pulley, an ink reservoir below the level of the disk, said pulley and disk being rotatively driven by said non-printing ribbon, a wick supported to rotate about an axis parallel to that of said disk and having a part rotating in the ink in said reservoir and a part arranged permanently out of said ink turning in contact with the periphery of said disk; said wick extending downward from said disk into the reservoir, and driving gears connecting said disk and rotary wick for rotating the wick from the disk.

49. In a typing machine, the combination with a writing ribbon consisting of threads and fibres of silk, compactly woven and inked to produce written characters of sharp outline, of means for accurately re-inking said ribbon during intermittent operation of said machine, to maintain an approximately uniform supply of ink in said writing ribbon at the typing position; said means including a thin edged inking member having a rolling contact with a small portion only of the width of one face of a ribbon member in said machine; a reservoir of ink; and means for applying a thin film of ink to the periphery of said thin edged inking member, which is sufficient to replace ink used in writing; said inking member being substantially non-ink-absorptive and lying above the ink supply in said reservoir.

50. In a typing machine, the combination with a writing ribbon, having a small reserve supply of ink, and woven compactly and of a thinness and inking to produce written characters of sharp outline, of means for accurately re-inking said ribbon during intermittent operation of said machine, to maintain an approximately uniform supply of ink in said writing ribbon at the typing position, and said means including a thin edged inking member having a rolling contact with a small portion only of the width of a ribbon member in said machine; a reservoir of ink; and means for applying a thin film of ink to said inking member, which is approximately sufficient to replace ink used in writing with the said machine; said inking member being substantially non-ink-absorptive and lying above the ink supply in said reservoir; said machine being equipped with at least one ribbon.

51. In a typing machine, a ribbon inking device, for maintaining an approximately uniform supply of ink in a ribbon at the typing position during intermittent operation of said machine, wherein a rotary ink applier is supplied with ink from a reservoir by an ink supplying means and said ink applier is opposed to a pulley between which and said ink applier a ribbon is fed endwise, characterized, in that the pulley is supported above the reservoir to rotate about an upstanding axis which is fixedly related to the reservoir, and said ink applier is supported above the reservoir to rotate about an upstanding axis and to move horizontally relative to the reservoir; and said pulley and said ink applier being urged toward a ribbon in said machine; said ink supplying means being so arranged as to

maintain contact with the periphery of the said ink applier.

52. In a typing machine, the combination with an inked ribbon formed of silk fibres, through 5 which the typed impressions are made in conventional way, and mechanism for traversing said ribbon longitudinally past the typing position, of means for maintaining a substantially uniform amount of ink in the inked ribbon at 10 said typing position during intermittent use of said machine; the said means comprising a rotary ink transfer element in the form of a rotary member having a narrow peripheral surface and arranged for rolling contact between said surface 15 and a ribbon in said machine and means for supplying said surface with ink in the form of an ink film of predetermined depth coextensive with said surface to thereby afford a controlled transfer of ink to a ribbon in amount accurately 20 regulated to replace ink used in writing with said machine; the peripheral surface of said transfer element being substantially non-ink-absorptive; and said machine being equipped with at least one ribbon.

25 53. In means for feeding ink to an ink transfer ribbon in a typing machine at a substantially uniform rate during intermittent use of said machine so as to maintain a substantially uniform quantity of ink in said ribbon at the typing 30 position, the combination with means for longitudinally traversing said ribbon, of a rotary ink transfer element arranged for rolling contact with a face of a ribbon in said machine, and having a ribbon-contacting surface of small 35 area; said ink being supplied to said ink transfer element under control in amounts accurately regulated to equal the amounts of ink lost in the typing operations for all practical purposes; and said machine being equipped with at least one 40 ribbon.

54. A typing machine in accordance with claim 53, in which the writing ribbon is formed largely of silk fibres and threads.

55. A typing machine in accordance with claim 53, in which a wick is used in supplying ink to a ribbon in said machine, and one end portion of said wick lying outside an ink well in said machine.

56. In a typewriting machine, the combination with an ink-bearing ribbon through which the typed impressions are made in conventional manner, and mechanism for traversing said ribbon longitudinally past the typing position, of means for maintaining an approximately uniform quantity of ink in said ribbon at said typ-

ing position during intermittent use of said machine, including at least one rotary ink transfer element and an ink reservoir and means for supplying ink from said reservoir to the lengthwise portion of said ribbon which is marked by the type of said machine in writing, in quantity accurately regulated to replace in said ribbon the ink lost therefrom as a result of the writing operation; and said machine being equipped with at least one ribbon.

5 57. An inking mechanism including a pressure roller and an inking disk disposed at opposite sides of an ink transfer ribbon and in rolling contact with the faces thereof, said roller and disk being mounted for movement relatively with respect to each other, means for applying, during intermittent use of said mechanism, a thin, uniform film of ink to said disk's peripheral surface for transfer to an ink transfer ribbon in said mechanism, and resilient means urging said disk and roller toward each other and into yielding contact with a ribbon in said mechanism; and said mechanism being equipped with at least one ribbon.

10 20 25 30 35 58. In a typing machine, equipped with a reserve supply of ink suitable for relinking a writing ribbon, the combination with a writing ribbon lightly impregnated with ink so that continued use of said ribbon would soon render it useless, of means for inking said ribbon continuously during intermittent operation of said machine, including means for conveying ink from said supply to said ribbon; said conveying means comprising rotary means and including a thin edged rotary member, said inking being done approximately even.

40 45 50 55 59. In a typing machine, the combination of a writing ribbon carrying the optimum quantity of ink for the character of impression desired, a substantially non-absorbent ink supply ribbon having at least one smooth, even surface, the two ribbons contacting with each other, an ink reservoir, and means for placing ink from said reservoir upon said ink supply ribbon in the right quantity to maintain the ink content of the writing ribbon substantially uniform and the same, and means for moving said ribbons so as to transfer said ink from said ink supply ribbon to said writing ribbon continuously during use of said writing ribbon, in uniformly even quantities, said ink being transferred in the form of at least one line, from the ink reservoir to the smooth surface of said supply ribbon.

CERTIFICATE OF CORRECTION.

Patent No. 2,074,969.

March 23, 1937.

GEORGE E. PELTON.

It is hereby certified that error appears in the printed specification of the above numbered patent requiring correction as follows: Page 12, first column, lines 54 and 62, claims 46 and 47 respectively, for the claim reference numeral "46" read 45; and that the said Letters Patent should be read with these corrections therein that the same may conform to the record of the case in the Patent Office.

Signed and sealed this 11th day of May, A. D. 1937.
